FLUID MACHINE

Aladar Hollander, Berkeley, Calif., assignor to
Byron Jackson Co., Berkeley, Calif., a corpora-
tion of Delaware

Application April 13, 1935, Serial No. 16,172

1 Claim. (Cl. 103—109)

This invention relates to improvements in double casing multi-stage centrifugal pumps especially adapted for the pumping of hot oil under relatively high pressures.

5 It is one of the principal objects of this invention to provide a double casing multi-stage centrifugal pump with a double suction first stage impeller in order that a relatively low entrance velocity may be maintained to prevent formation 10 of vapor in the impeller inlet or suction column and to thereby improve the operating characteristics of the machine and also to prevent vapor locking.

Other objects and advantages of the invention 15 will become apparent as the nature of the same is more fully understood from the following description and accompanying drawing, wherein is set forth what is now considered to be a preferred embodiment. It should be understood, however, 20 that this particular embodiment of the invention is chosen principally for the purpose of exemplification and that variations therefrom in details of construction or arrangement of parts may accordingly be effected and yet remain within the 25 spirit and scope of the invention as the same is set forth in the appended claim.

The drawing illustrates a vertical cross-sectional view through the shaft axis of a double casing, multi-stage, centrifugal pump employing 30 my invention.

One of the problems met with in a high speed, double casing pump is the formation of vapor in the suction passages leading into the inlet eye of the first stage impeller when pumping volatile 35 fluids such as hot oil, hot feed water for boilers or inherently volatile fluids such as butane. The formation of vapor in the suction passages deleteriously affects the operating characteristics of the machine and therefore should be eliminated 40 if possible.

In the ordinary pumps of this character, the formation of vapor in the suction passages is due largely to their necessarily restricted size and therefore the suction fluid must travel at a very 45 high velocity in order to keep pace with suction created by the first stage impeller and as a result thereof, if the suction fluid can not flow into the first stage impeller with sufficient speed to satisfy its demand, a reduction of pressure or partial 50 vacuum will be created in the inlet eye of this impeller. As will be appreciated when pumping highly volatile fluids, a slight reduction in pressure will in many cases cause vapor to develop in the fluid and thus impair the operating efficiency of 55 the machine.

After considerable experimentation, I have discovered a simple and effective method of correcting this fault, which method resides in providing the machine with a double suction first stage impeller whereby the suction passages may have 5 substantially twice the effective area and thus practically reducing the velocity of the inflowing fluid to one-half. As a result thereof, vaporization of the suction fluid is substantially eliminated.

Heretofore it has been thought impossible to provide a double casing pump with a double suction first stage impeller, due to the difficulty of providing a suction fluid passage to the inner inlet eye of this impeller. This difficulty I have effectively overcome by the arrangement of the suction and pressure chambers formed between the two casings of the machine and by placing the double suction impeller within the suction chamber and thereby making possible a short 10 direct suction passage of relatively large area each side of this impeller, whereby the inflowing fluid 15 may flow smoothly and easily into the two suction inlet eyes of the first stage double suction impeller.

The double casing multi-stage centrifugal pump having a double suction first stage impeller as illustrated in the drawing, may include an outer or pressure casing 1, which will be referred to as the housing in order to distinguish it from the 20 inner or impeller casing 2. The bore of the housing may be divided into a suction area 4 and a pressure area 3 separated by a shoulder seat 5. The suction area 4 is shown of less diameter than the diameter of the pressure area 3 in order to 25 provide the radial seating shoulder 5 but it is to be understood that any other arrangement may be provided which will provide a suction area and a pressure area separated by a suitable form of seat.

In the machine shown, the housing is provided 30 with an integrally cast suction end 6 but a separate end bolted on may be used if preferred. The pressure end of the housing is provided with a flange 7 to which the end cover 8 may be securely fastened as by bolt means 9. The housing is provided 35 with a suction nozzle 10 having a suction passage 11 for communicating the suction area 4 with the exterior of the housing and a discharge nozzle 12 provided with a discharge passage 13 for communicating the pressure area with the 40 exterior.

The impeller casing 2 is generally cylindrical in exterior form, having a suction area 14 of a diameter less than the diameter of the suction area 15 of the housing bore so as to provide therebetween 55

- a suction chamber 15, while the pressure area 16 of the casing is of greater diameter than its suction area 14 to provide therebetween a radial shoulder seat 17 arranged to cooperate with housing seat 5 to form therewith an effective fluid seal. The pressure area 16 of the casing is of less diameter than the diameter of the housing pressure area 3 so as to form therebetween a pressure chamber 18.
- 10 When the casing is mounted within the housing as shown in the drawing, the respective seats 17 and 5 are maintained in sealing engagement by the resilient gasket 19 acting between cover 8 and the adjacent end of the casing when the machine is not in operation and by this gasket plus the pressure difference between the suction and pressure chambers, which acts to drive the inner casing seat with considerable force against the housing seat, when the pump is in operation.
- 15 20 The suction end of the casing is provided with a double suction impeller cavity 20 which in the machine shown is within the suction area 15 thereof but may be differently located, if preferred. The casing is provided with twelve single suction impeller cavities 21, all located within the pressure area. An impeller shaft 22 extends axially through the housing and casing and is provided with a double suction impeller 23 for the double suction cavity and a single suction impeller 24 for each of the single suction cavities formed in the casing.
- 25 30 The customary stuffing boxes and bearing are provided for the shaft and the impellers are mounted thereon in the usual manner and therefore need not be described in detail. The number and arrangement of single suction impellers may be varied to suit any particular condition for which the machine may be made to operate.
- 35 40 The important difference between this pump and other double casing pumps is the inclusion of a double suction first stage impeller and the manner of providing suction passages to each side thereof. It will be noted that the first stage double suction impeller is spaced from its nearest single suction impeller in order to provide sufficient room for the inlet passage 25, which passage is of relatively large area and communicates the inwardly directed inlet eye of the double suction impeller with the suction chamber 15. The
- 45 50 55 60 65 double suction impeller cavity is also spaced a sufficient distance from the end of the casing to enable the provision of a relatively large inlet passage 26 to communicate the other inlet eye of the double suction impeller with the suction chamber. In this machine, the suction chamber is made of sufficient size to permit the suction passage 11 to be of relatively large area as compared with the area of the discharge passage 13 and likewise to provide large and streamlined inlet passages 25-26 to the opposite sides of the double suction impeller whereby the suction fluid may flow into the double suction impeller in a relatively leisurely manner along well formed streamlined passages and as a result thereof, the tendency of the fluid under treatment to vaporize will be substantially eliminated.

A fluid passage 27 receives the fluid discharged

from the first stage impeller cavity and conveys it serially through each of the single suction impeller cavities and finally discharges the fluid into the pressure chamber 18 from which it may be discharged through passage outlet 13.

It will be understood that the impeller casing is parted in a plane perpendicular to that shown in the drawing, whereby the shaft and impellers may be mounted therein.

As shown in this embodiment, the first stage 10 double suction impeller and cavity are smaller in diameter than the single suction impellers and cavities in order that the suction area of the casing may be reduced in diameter to provide the shoulder seat 17. However, it is to be understood 15 that all of the impellers and cavities may be of the same diameter and the pressure area increased slightly in diameter to provide a suitable seat, but the construction shown is preferred.

The preference to the shown construction, 20 wherein the first stage double suction impeller and cavity therefor are of smaller diameter than the single suction impellers and cavities, is due to the provision of the seating shoulder 17 without necessitating an increase in the diameter of 25 the pressure section of the impeller casing and therefore it is not necessary to increase the size of the housing which, due to the stress caused by the relatively high internal pressure, should be made as small in diameter as possible. Also, 30 due to this arrangement, sufficient room is provided for the fluid passage to traverse the impeller casing from the discharge of the first stage impeller cavity to the inlet passage of the second stage impeller cavity.

Having fully described a preferred embodiment of the invention, it is to be understood that it is not to be limited to the details herein set forth, but the invention is for the full scope of the appended claim.

I claim:

In a double casing multi-stage centrifugal pump, a housing having longitudinally spaced suction and pressure areas separated by an annular seat and suction and pressure passages communicating their related suction and pressure areas with the exterior thereof, an impeller casing within said housing having longitudinally spaced suction and pressure areas separated by an annular seat which engages said housing annular seat, said casing having a plurality of single suction impeller volutes formed in the pressure area and a double suction impeller volute formed in the suction area, an impeller shaft extending through said single and double suction impeller volutes, 45 a double and a plurality of single suction impellers mounted upon said shaft for operation in their related volutes, said casing having a suction opening formed in its suction area and aligned with said housing suction passage, fluid passages 50 in said casing leading directly from said suction opening to the inlets of the double suction impeller, the discharge of the double suction impeller being led successively through the single suction impellers and finally discharging into the 55 pressure chamber.

ALADAR HOLLANDER.
